HYDRAULIC TURBINE

1,092,091.

Specification of Letters Patent. Patented Mar. 31, 1914.

Application filed March 24, 1913. Serial No. 757,259.

To all whom it may concern:

Be it known that I, JEAN F. CACHIN, a citizen of the Republic of Switzerland, residing at Milwaukee, in the county of Milwaukee and State of Wisconsin, have invented a certain new and useful Improvement in Hydraulic Turbines, of which the following is a specification.

This invention relates to improvements in the construction of hydraulic turbines and particularly to improvements in the construction of turbines of the vertical Francis type.

An object of the invention is to provide a hydraulic turbine which is simple in construction and in which the normally inclosed turbine elements are readily accessible and removable.

Another object is to provide a construction in which the size of the inspection pit below the turbine is reduced to a minimum.

Still another object is to permit the use of suitable hoisting machinery, such as overhead cranes or other constantly available devices, for manipulating the turbine elements during assembling and removal thereof.

It is, moreover, an object of the present invention to provide means for permitting ready removal of the turbine runner and guide vanes from the lower end of the turbine without necessitating disturbance or removal of heavy elements such as the main turbine shaft and the stationary upper turbine casing.

Another object is to provide a telescopic draft tube portion which may be furnished as an article of manufacture and readily applied to existing turbine installations.

A clear conception of an embodiment of the invention may be had by referring to the drawing accompanying and forming part of this specification, in which like reference characters designate the same parts in the various views.

Figure 1 is a fragmentary central vertical section through substantially one half of a vertical hydraulic turbine, showing the turbine runner being hoisted into position and showing one of the guide vanes suspended from its hoisting rig. Fig. 2 is a fragmentary central vertical section through substantially one-half of a vertical hydraulic turbine, showing the runner in place and

the runner point being hoisted into position, and showing one of the guide vanes suspended from its hoisting rig. Fig. 3 is a fragmentary central vertical section through substantially one half of a vertical hydraulic turbine, showing the runner, runner point and guide vane in position, and showing the telescopic draft tube and lower guide vane ring being hoisted into position. Fig. 4 is a fragmentary central vertical section through substantially one half of a vertical hydraulic turbine, showing the turbine completely assembled.

The spiral inlet turbine casing 3 is provided with a central bore and is supported upon the foundation 19. The speed ring 6, which consists of a pair of spaced rings connected by stationary guiding and stiffening ribs, is fitted into the central bore of the casing 3. The upper guide vane ring 12 is mounted concentrically within the speed ring 6 and forms a portion of the upper normally stationary inclosing casing of the turbine. The main turbine shaft 8 is supported vertically within the upper turbine casing and is suspended from a suitable thrust bearing of the usual type, not shown, which is located above the turbine. The main turbine shaft 8 is provided with a central bore or passage 18 which extends throughout the entire length of the shaft 8.

The inspection pit 1 is formed below the turbine and surrounds the telescopic draft tube casing 5. The pit entrance 2 leads from the pit 1 to the interior of the power house through an opening at the right of the turbine as disclosed.

The lower guide vane ring 13 is supported upon the upper end of the telescopic draft tube casing 5, and when in assembled position is fastened to the speed ring 6. The lower end of the telescopic draft tube casing 5 connects with the stationary draft tube 4, the joint between these elements being suitably packed.

The inlet casing 3, speed ring 6, guide vane rings 12, 13, and draft tube casing 5, constitute normally stationary turbine elements.

The turbine runner 9 when in assembled position, see Fig. 4, is secured to the lower end of the main turbine shaft 8 and has its discharge end directed into the telescopic

draft tube casing 5. The runner point 10 is secured to the mid portion of the runner 9 and serves to properly guide the water discharged through the blades of the runner 5 into the draft tube.

The runner 9, shaft 8, and runner point 10, constitute normally rotatable turbine elements.

The turbine gate mechanism consists of 10 a series of movable guide vanes 7 which are journaled in the upper and lower guide vane rings 12, 13. The upper ends of the guide vane shafts are provided with the usual gate actuating mechanism, consisting of cranks, 15 the inner free ends of which are connected with a guide vane actuating ring. The actuating ring is shiftable about the turbine axis by means of a guide vane actuating cylinder 11 in the usual manner. The guide vanes 7 and the actuating mechanism therefore constitute normally shiftable turbine elements.

The mechanism for manipulating the turbine elements during assembling and dismantling of same, consists of cables or ropes 25 14, 17, which are secured at their upper ends to any suitable hoisting mechanism, such as a power house crane. The rope 14 during manipulation of lower turbine elements extends through the passage 18 formed within the main turbine shaft 8 and may be connected with the turbine part to be manipulated by any suitable means such as a manipulating block 15, a hoisting beam 16, or 30 eye-bolts. The ropes 17, of which there may be a number, are connected to the upper extremities of the guide vane actuating shafts by means of suitable eye-bolts.

In describing the utility of this invention 40 the logical sequence of operations necessary during assembling of the turbine will be given, and it should be understood that during dismantling of the turbine the sequence of operations would be the reverse. With the turbine dismantled, that is with the turbine runner 9, runner point 10, guide vane 7, lower guide vane ring 13, and telescopic draft tube casing 5 removed, as disclosed in Fig. 1, the first step in the operation of assembling is to raise the runner 9 into place 50 and secure same to the lower extremity of the main turbine shaft 8. This can be done as disclosed in Fig. 1, by setting the runner 9 upon the manipulating block 15 and attaching the latter to the end of the manipulating rope 14. By pulling upwardly on the rope 14, the runner 9 can be readily hoisted into its proper position and held there until it is secured to the shaft 8, as disclosed in 55 Fig. 2. After the turbine runner 9 has been properly secured to the shaft 8, the runner point 10 is to be hoisted concentrically within the runner 9 and secured thereto. This may be done as disclosed in Fig. 2 by setting 60 the runner point 10 in a suitably formed re-

cess of the manipulating block 15 and raising the rope 14 connected with the block. When the runner point 10 is raised to its proper position within the runner 9, it is firmly secured to the runner as shown in Fig. 4. With the turbine runner completely assembled, the next operation is to raise the movable guide vanes 7 into their proper positions relative to the normally stationary upper guide vane ring 12. This may readily be done by attaching the rope 17 to the upper end of the actuating stem of each of the individual guide vanes 7 and hoisting the individual guide vanes 7 into their proper positions as indicated in Fig. 3. With the 75 guide vanes 7 properly positioned within the upper guide vane ring 12, the lower guide vane ring 13 may be brought into its proper position relative to the speed ring 6 and guide vanes 7, either by raising the ring 13 80 into place independently or by simultaneously raising both the ring 13 and the telescopic draft tube casing 5 to the position as indicated in Fig. 4. The hoisting of the telescopic draft tube casing 5 may be readily 85 accomplished by inserting the cross-beams 16 through suitable manholes formed in the casing 5, and securing the rope 14 to the mid position of the beam 16. By manipulating the rope 14 from above the shaft 8, the casing 5 and lower guide vane ring 13 may 90 readily be brought into their proper positions and secured to the adjoining stationary turbine elements.

By forming the draft tube casing 5 telescopic within the stationary draft tube 4, the size of the inspection pit 1 is reduced to a minimum. The removability of the draft tube casing 5 permits ready inspection of the interior of the turbine for removal of parts 100 and for making repairs. The formation of vertical manipulating passages through the upper portion of the turbine and provision of hoisting means extending through these 105 passages, provides simple means for readily centering the various turbine elements and for manipulating them during dismantling and assembling of the turbine.

It will be noted that the telescopic portion of the draft tube casing 5 may readily be 110 furnished as an article of manufacture, to be incorporated in existing turbine installations.

It should be understood that it is not desired to be limited to the exact details of 115 construction shown and described, for obvious modifications will occur to a person skilled in the art.

It is claimed and desired to secure by Letters Patent,—

1. The combination of turbine elements some of which forming an inclosing casing, other of said elements being within said casing, said casing having a lower one of said elements removable, and another of said ele-

- ments having an opening therethrough for manipulation of lower of said turbine elements.
2. The combination of turbine elements some of which forming an inclosing casing, other of said turbine elements being within said casing, said casing having a lower one of said elements removable, and one of said turbine elements being a turbine shaft 10 extending through the upper portion of said casing and having an opening therethrough for manipulation of lower of said turbine elements.
3. In combination, an inclosing casing, a runner within said casing, said casing having a removable lower portion, and a vertical runner shaft extending through the upper portion of said casing and having an opening therethrough for manipulation of 20 said runner.
4. In combination, an inclosing casing, a runner within said casing, said casing having a lower portion telescopic within adjacent structure, and a vertical runner shaft 25 extending through the upper portion of said casing and having an opening therethrough for manipulation of said runner.
5. The combination of turbine elements some of which forming an inclosing casing, other of said elements being within said casing, said casing having a lower one of said elements telescopic within adjacent structure, and another of said elements hav-
- ing an opening therethrough for manipulation of lower of said turbine elements. 35
6. In combination, a runner, a normally fixed upper casing having an opening therethrough, a shaft within said opening, said shaft having a passage therethrough for manipulation of said runner from above, 40 and removable means at the lower end of said casing for permitting access to said runner during manipulation thereof.
7. In a turbine, a normally fixed upper inclosing casing, and a lower casing telescopic 45 within adjacent structure for permitting access to the interior of said casings.
8. In a turbine, a casing, and a telescopic draft tube for permitting access to the interior of said casing. 50
9. In a turbine in combination, turbine parts with a draft tube portion, and a second draft tube portion telescopic relative to said first draft tube portion.
10. As an article of manufacture for a 55 turbine, a draft tube portion telescopic in relation to the remainder of the turbine draft tube.
- In testimony whereof, the signature of the inventor is affixed hereto in the presence of two witnesses. 60
